CLAUD R. BAUCOM, OF APEX, NORTH CAROLINA.

MAIL-BAG CATCHING AND DELIVERING APPARATUS.

1,297,060.

Specification of Letters Patent. Patented Mar. 11, 1919.

Application filed January 24, 1917. Serial No. 144,254.

To all whom it may concern:

Be it known that I, CLAUD R. BAUCOM, a citizen of the United States, residing at Apex, in the county of Wake and State of North Carolina, have invented certain new and useful Improvements in Mail-Bag Catching and Delivering Apparatus, of which the following is a specification.

This invention relates to an improvement

- 10 in mail bag catching and delivering apparatus and has for its purpose to provide an apparatus which may be arranged to have parts thereof attached to a car and other parts located along the track to act in conjunction with the parts carried by the car to catch and deliver mail bags irrespective of whether the train may be moving at a high or a low rate of speed in its travel; the parts being so arranged that the structure may be
- 15 used upon a single or double track road and will act with equal effectiveness in transferring the mail bags either to or from the train.

An object of the invention lies in so constructing the parts by which the mail bags are held subsequent to delivery that the mail bags will be received in a basket-like container to be held against casual displacement and until the discharge interval, when operating parts will cause actuation of movably mounted parts of the holding structure and the bags will be released to fall by gravity from the holding means.

A further object is to provide such mounting for the structure that the delivery and catching apparatus can be moved into and from the operative position, thus avoiding any considerable protrusion of the parts on the side of the car or of sections closely adjacent a track when the parts are not in use.

A still further object is to provide means arranged in conjunction with the portions by which the mail bags are supported subsequent to the discharge which means will hold this apparatus normally in the bag retaining relation and subsequent to the actuation thereof to discharge the bags, will again return the parts to the normal or holding position.

With the above and other objects in view, my invention consists of such novel features of construction and combination of parts which will be hereinafter set forth in connection with the drawings, and then more particularly pointed out in the claims.

In the drawings:—

Figure 1 is a view in perspective of fragmentary portions of a car and a ground device showing one form which the parts might take when adapted for use upon a single 60 track road.

Fig. 2 is a fragmentary horizontal sectional view, to better illustrate the bag supporting means.

Fig. 3 is a somewhat diagrammatic plan 65 view and illustration of the arrangement of ground devices for a single track road, the delivering and receiving devices being shown associated with a portion of a track.

Fig. 4 is a fragmentary view showing the 70 arrangement of parts for the delivery of bags from the ground device to the car.

Fig. 5 is an elevational view to better disclose the baskets as carried by the car.

Fig. 6 is a view similar to Fig. 4 illustrating parts mounted to deliver bags from the car to the ground.

As has been stated, the device includes a bag receiving and holding means to be mounted either upon the car or upon the 80 ground device to have the mail bags placed therein, and means mounted in an opposed relation to act upon parts of the basket to release the bags and cause the same to be delivered, means also being used to catch the 85 bags as delivered.

To all intent and purposes, the parts as mounted upon the car and upon the track device will be substantially the same in construction and operation in either of the interchanged mountings, and for the most part any changes which may be resorted to will be only for the purpose of adapting the structure to the peculiar positions of use.

The mail bag receiving basket in which 95 the bags are to be placed for delivery is supported by the bracket arm 1 which has bearings 2 and 3 formed in conjunction therewith and spaced apart so that as this bracket is mounted with the hinge pin 4 100 passing through the bearings 2 and 3, the bracket 1 will be mounted to swing around the hinge pin and to extend laterally therefrom. The bracket arm 1 has bearings 5 provided on the lower end thereof and a 105 shaft 6 is mounted in the bearings 5 to be capable of turning movement and to extend substantially at right angles to the vertical disposition of the hinge pin 4. Rods 7 are formed in conjunction with the shaft 110

6 and extend from one side thereof to take substantially a rack formation, the side members 8 being disposed to extend from the bracket arm 1 to form an upstanding side substantially around the rack portion. This side 8 is preferably made of grillework or of wire fabric and a spring 9 is mounted around the shaft 6 with one of its ends hooked over one of the rods 7 and the remaining end hooked back of the bracket arm 1 so that the spring normally exerts force to hold the rack portion in the position in which it is swung up to form a bottom for the side members 8, and thus a mail bag receiving basket is formed. The hinge pin 4 can be connected upon a car, upon a post, or upon any other support which may be disposed to carry the same, and thus the receiving basket structure can be swung to and from position occupied in use. A trip arm 10, which is preferably curved at its ends, is formed as a part of or in connection with the shaft 6 to extend in a substantially vertical position when the rack portion is raised by the action of the spring 9, and thus this trip arm is disposed in such a relation as it may be engaged to be forced over against the action of the spring 9, the rods 7 supporting the rack will be swung downwardly and the bottom of the receiving basket will thus be left open. As has been stated, the mail bag receiving basket structure as described can be mounted upon the car, upon a post mounted adjacent the track or upon any other suitable support, and when the hinge pin 4 is connected upon a car, it will be mounted inside of the door so that the bracket arm 1 can be swung to extend laterally from the side of the car or can be swung within the car to bring the receiving basket into the car, and therefore it will be apparent that when the hinge pin is connected upon a post located adjacent the track, the basket structure can be moved to be disposed to project toward a car moving on the track or can be swung to be moved from the track. In Fig. 1 I have shown the hinge pin 4 connected with the inside of a car wall adjacent the door opening thereof so that the basket structure can be swung into and to extend from the car, and where this structure is used, it is necessary that along the track at the point where the mail bags are to be discharged from the basket, means should be provided to engage the trip arm 2 and thus cause downward swinging of the rods 7 thus turning the shaft 6 against the force exerted by the spring 9. With this purpose in mind, I mount the post 11 adjacent the track and provide an arm 12 to extend inwardly therefrom at such a height that as the car passes with the basket structure extended, the arm 12 will strike the trip arm 10, and will cause this trip arm to ride

under the same, thereby swinging the basket structure downwardly and opening the bottom of the bag receiving basket so that the bags will fall therefrom. To catch the bags, I dispose a basket 13 upon the post 11, or mount the same at any other suitable point where it will be disposed to catch the mail bags as they fall thereinto as discharged from the bag receiving basket. When the car is moving at a high rate of speed, there is tendency for the mail bags to be sucked under the car and there is possibility that the bag would fall beneath the wheels of the car, and that they and the contents would be mutilated. To prevent the possibility of this occurring, I mount the bar 14 upon the side of the car and provide the protecting fingers 15 disposed to extend outwardly and downwardly from the bar 14 constituting a guiding chute. In this connection it is perhaps possible that the bar 14 be disposed somewhat obliquely upon the side of the car as from this arrangement a better deflecting action may be obtained. The structure as described and as shown in Fig. 1, is adaptable for use upon a double track road where the trains travel in one direction only, and where the mail bags are to be delivered from apparatus carried by the car and caught by apparatus mounted on the ground adjacent the track, however, it will be seen that by a reversal of the parts the mail bags may be delivered from a track device and caught by apparatus carried by the car. In Fig. 3 I have disclosed in a somewhat diagrammatic manner and yet in plan, one arrangement which might be made of the parts for use upon a single track road, and as here shown, a supporting post 16 is mounted adjacent the track 17 and has the mail bag delivering baskets 18 and 19 carried therefrom by being mounted on the hinge pins 20 and 21. The bracket arms 1 carried on the hinge pins 20 and 21 respectively are arranged to have the shaft 6 disposed with the rods 7 extending in opposite direction therefrom, and thus as the baskets 18 and 19 may be selectively swung to extend adjacent the track 17, the device will be adapted for use in connection with a car or train traveling in either direction, it of course being understood that the basket 18 being used when the train is moving in one direction and the basket 19 for a train moving in the opposite direction, and that when the mail bags are to be delivered from the train to the track device, both baskets will be swung to the position away from the track. With the use of the structure as just described, it is also possible that the bag catching apparatus may be arranged to be moved into and out of the position for use and with this in mind, I mount a post 22 in the base 23 to be capable

of turning movement on its axis and provide a handle 24 by which this turning can be accomplished. To hold the post 22 in desired adjusted position the notches 25 and 26 are provided in the base 23 on opposite sides and the handle 24 is mounted to be capable of swinging movement so that as the post is brought to its desired adjusted position, the handle can be swung down to rest within the notch 25 or the notch 26 and then the post will be held positively against casual turning movement and can be turned only after the handle 24 has been again manually raised to be disengaged from the notch. The post 22 has the supporting arms 27 and 28 extending laterally therefrom and a basket structure 29 is mounted between the supporting arms to be carried with the open top thereof disposed at one side of the post. An arm 30 is carried by the post 22 in rigid mounting to overhang the basket 29, and as the post is adjusted to swing the basket 29 adjacent the track 17, the overhanging arm 30 will be disposed to engage with the trip arm of the basket carried by the car and in this way the rack of the bag receiving basket will be swung downwardly to discharge the mail bags into the bag catching basket 29. The bar 14 having the fingers 15 extending therefrom to form the fender can be used upon the car or can be dispensed with as may best suit the particular conditions of use. To permit the basket as carried by the car to be folded or moved to a position where it offers very little projection from the side of the car, the parts can be arranged as is better shown in Figs. 4 and 5, where the basket frame 31 is mounted in the bearings 32 carried on the side of the car and the basket is made up of a flexible mesh 33. A handle 34 is connected with the frame to extend within the car and by manipulation of this handle the frame can be raised to a position as shown by the dotted lines in Fig. 5 where the flexible mesh 33 will be brought to lie closely adjacent the side of the car. In this connection, it is also desirable that the arm as carried by the car is to engage with the trip arm of the bag receiving basket as carried by the ground device be made to be extensible from the car, and with this in view, I mount the bracket structure 35 within the car and dispose the arm 36 through this bracket structure and through an opening in the side of the car to be slidably mounted so that by grasping the handle 37 this arm 36 may be moved to extend from the side of the car or may be withdrawn to offer very little if any projection from the car.

From the foregoing it will be seen that I have provided a structure which is so arranged that the mail bags can be thrust upon the supporting rack and the bracket arms

may then be swung to a position that the trip arm thereof will be engaged by the arm of the coöperating device, to cause discharge of the mail bags, thus doing away with the necessity of the mail clerk placing his head 70 or any part of the body beyond the side of the car where posts or other obstructions might be encountered; that the arrangement of the various parts of both the car and ground devices makes it possible to swing 75 the coöperating parts to be moved from the position in which the track, in the case of the ground device, and from a position of any great extent from the side of the car in the car device, and further that as the mail bags are discharged from the supporting rack of the receiving basket they will be 80 positively directed into the catching basket and the supporting rack will be again returned to such a position that other mail bags may be placed in the receiving basket faster to be held thereby for subsequent delivery.

While I have here shown and described only such specific forms and arrangements 90 of the parts and have set forth only specific adaptations, it will be understood that a number of changes and modifications may be resorted to in the form and arrangement of the various parts entering into the construction and making up of the completed apparatus and hence I do not wish to be limited to the exact disclosure but rather only to such points as may be set forth in the claims.

I claim:

1. A mail bag delivering apparatus comprising a bracket arm provided with bearings, a hinge pin mounted in conjunction with a car and having the bracket arm mounted thereon to be capable of swinging movement into the car and to project laterally from the car, a shaft mounted in the bearings of said bracket arm provided with a plurality of rods extending therefrom to form a mail bag delivering rack, means to normally hold said shaft resiliently in such a position that the rack portion is positioned to support mail bags, and a trip arm formed in conjunction with said shaft to be engaged by a ground device located adjacent to the path of travel of the car to cause turning of the shaft to incline the delivering rack portion and to thus cause discharge of the mail bags therefrom.

2. A mail bag delivering apparatus comprising a bracket arm provided with bearings, a hinge pin to be mounted in conjunction with a supporting device having the bracket arm mounted thereon to be capable of swinging movement into and out of the position for use, a shaft mounted in the bearings of said bracket arms provided with a plurality of rods extending therefrom to form a mail bag delivering rack, a side por-

tion acting with the rack portion to provide a basket, means to normally hold said shaft resiliently in such a position that the rack portion is positioned to hold mail bags, and 5 a trip arm formed in conjunction with said shaft to be engaged by an arm mounted in a position opposed to the mounting of the hinge pin to cause turning of the shaft to incline the rack portion and to thus cause 10 discharge of the mail bags therefrom.

3. A mail bag delivering apparatus comprising a bracket arm provided with bearings, a hinge pin to be mounted in conjunction with a supporting device having the 15 bracket arm mounted thereon to be capable of swinging movement into and out of the position for use, a shaft mounted in the bearings of said bracket arms provided with a plurality of rods extending therefrom to 20 form a mail bag delivering rack, a side portion acting with the rack portion to provide

a basket, means to normally hold said shaft resiliently in such a position that the rack portion is positioned to hold mail bags, a trip arm formed in conjunction with said shaft to be engaged by an arm mounted in a position opposed to the mounting of the hinge pin to cause turning of the shaft to incline the rack portion and to thus cause discharge of the mail bags therefrom, and 25 means mounted in conjunction with the car below the disposition of the side receiving rack when the bracket arm is swung to the laterally disposed position to cause deflection of the mail bags from the car. 30 35

In testimony whereof I affix my signature in presence of two witnesses.
